J. M. SEYMOUR, JR.
OIL BURNER.
APPLICATION FILED DEC. 24, 1919.

1,416,424.

Patented May 16, 1922.

UNITED STATES PATENT OFFICE.

JAMES M. SEYMOUR, JR., OF NEWARK, NEW JERSEY.

OIL BURNER.

1,416,424.

Specification of Letters Patent. Patented May 16, 1922.

Application filed December 24, 1919. Serial No. 347,075.

To all whom it may concern:

Be it known that I, JAMES M. SEYMOUR, Jr., a citizen of the United States, residing at Newark, in the county of Essex and State 5 of New Jersey, have invented certain new and useful Improvements in Oil Burners; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 The present invention relates, generally, to improvements in oil burners for various kinds of boilers and furnaces, and for any other similar uses; and the invention has 20 reference, more particularly, to a novel and highly efficient construction of circulating oil burner.

The invention has for its principal object 25 to provide a novel construction of oil burner provided with means for constantly circulating the oil therethrough and gyrating the same about the spray discharge orifice regardless of the position of the needle valve which co-operates with the latter to close 30 and to regulate the degree of opening thereof.

In the common types of oil burners, as 35 heretofore used, and which are designed to eject a spray of oil from a discharge orifice, controlled by a suitable needle valve, by gyrating the oil in back of and about the said discharge orifice, a great disadvantage arises 40 from the fact that when the needle valve is nearly closed the flow of oil through the discharge orifice is so small that the centrifugal, rotating or gyrating motion of the oil is so slowed down, and even in some instances stopped altogether, that the spraying effect of the discharge is prevented, and consequently the oil dribbles or seeps out of the 45 discharge orifice without producing the desired and necessary spray, thus greatly impairing the efficiency of the burner.

Another disadvantage of this type of oil burner is that the oil is so slowed down in 50 its movement through the burner, when the discharge orifice is almost closed, that said oil becomes cooled and loses its proper viscosity, tending to gum up the interior chambers and passages of the burner to the 55 further impairment of the efficiency of the burner.

It is the object of my present invention to overcome the above mentioned disadvantages in oil burners of the spray type, and to this end I provide a novel construction of burner 60 having means for circulating the oil therethrough and at the same time producing the desired gyrating motion thereof in back of and about the needle valve controlled discharge orifice, the oil being kept, by means 65 of a feed pump, constantly flowing to the discharge orifice, and from that point back to the suction side of said pump, thus producing a circulation through the burner so constant that the oil,—if it is not allowed to 70 enter the fire box through the needle valve controlled discharge orifice, keeps up its movement or flow through the burner, so that whenever the needle valve opens the discharge orifice to any desired degree, the 75 oil will be in proper motion, at a proper temperature and at a proper condition of viscosity to immediately eject itself through said discharge orifice with the desired spray effect. A further advantage of my novel 80 construction of circulating oil burner lies in the fact that, no matter whether the needle valve controlling the discharge orifice is closed or open to any degree from minimum to maximum opened position, the gyrating 85 effect upon the oil is the same, so that when the orifice is open to any degree the oil will be ejected therefrom in a spray, this being due to the fact that the oil is permitted to travel or circulate through the burner con- 90 stantly at a fixed speed regardless of the position of the needle valve relative to the discharge orifice.

Another object of my invention is to provide a construction of oil burner which will 95 permit of a plurality of burners being coupled in series in the same oil supply line.

Other objects of the present invention, not at this time more particularly enumerated, will be clearly understood from the follow- 100 ing detailed description of the same.

With the various objects of the present invention in view, the same consists, primarily, in the novel construction of circulating oil burner hereinafter set forth; and, the invention 105 consists, furthermore, in the novel arrangements and combinations of the various devices and parts, as well as in the details of the construction of the same, all of which will be hereinafter more fully described, and 110 then finally embodied in the claims appended hereto.

The invention is clearly illustrated in the accompanying drawings, in which:—

Figure 1 is a face view of a portion of a furnace or boiler fire-box equipped with a novel construction of circulating oil burner, the relation of the latter to a feed pump and source of oil supply being also illustrated thereby; Figure 2 is a vertical longitudinal section taken on line 2—2 in said Figure 1, said view being drawn on an enlarged scale; Figure 3 is a detail transverse section taken on line 3—3 in said Figure 2; Figure 4 is a detail transverse section taken on line 4—4 in said Figure 2; and Figure 5 is a detail view illustrating a plurality of my novel circulating oil burners connected in series in the same oil supply line.

Similar characters of reference are employed in all of the hereinabove described views, to indicate corresponding parts.

Referring now to said drawings, the reference-character 1 indicates a fire-box provided with a burner port 2 having any suitable construction or arrangement of cover-plate 3. Said cover-plate 3 is provided with a suitably located opening 4 with which is connected the discharge end of an air delivery pipe or conduit 5. Mounted within the discharge end of said air delivery pipe 5 is the novel construction of circulating oil burner made according to and embodying the principles of my present invention, the same comprising a rearwardly tapering conical body portion 6 arranged with its forward end, or end of largest diameter, facing toward the fire-box interior. The forward end of said body portion 6 is open, and is internally threaded to receive, in closed relation thereto, an externally threaded circular cap-plate 7 provided with a centrally disposed discharge orifice 8. Connected with the rearward small end of said conical body portion 6, preferably as an integral part thereof, is a rearwardly extending neck 9 provided with a central internally threaded longitudinal opening 10, through which extends a valve stem 11 provided with a screw threaded portion 12 co-operating with the internally threaded portion of said opening 10. The outer end of said neck 9 is provided with an annular packing seat 13, in which is arranged a suitable packing 14 to surround said valve stem 11, a packing retaining cap 15 being threaded to the external extremity of said neck 9. Said valve stem extends rearwardly and outwardly through said cap 15, and thence through a bearing block 16 mounted in the wall of said air delivery pipe 5 to project exteriorly of the latter, the outer extremity of said valve stem having a hand-wheel 17 fixed thereon, wherewith said valve stem may be properly manipulated. The inner end of said valve stem

is formed to provide a tapered needle valve portion 18, which co-operates with said discharge orifice 8 to open or close the same at the will of the operator. The interior of said body portion provides a rearwardly diminished conical chamber 19 in back of said cap-plate 7.

Connected with said body portion 6 is an oil delivery or intake pipe 20, the same being so located relative to said body portion 75 that its passage 21 enters the chamber 19 tangent to its greatest diameter immediately in the rear of said cap-plate 7. Also connected with said body portion 6 is an oil return or outlet pipe 22, the same being so 80 arranged that its passage 23 is connected in communication with the rear or diminished outlet end 24 of the conical chamber 19. In order to aline the intake and outlet pipes in parallel arrangement, which is the arrangement I prefer, I provide in connection with the exterior wall of said body portion 6 a rib or longitudinal boss 25 in which is provided a passage 26 which interconnects the passage 23 with the outlet end 24 of said chamber 19.

The reference-character 27 indicates any suitable source of oil supply, from which leads to said intake pipe 20 an oil supply or delivery pipe line 28, in which is connected 95 a force pump 29, of any desired type, for feeding the oil in constant flow from said source of supply to said oil burner. Connected with said outlet pipe 22 is an oil return pipe line 30 leading back to said source of supply 27.

When the novel construction of oil burner above described is in operation, the valve stem 11 is manipulated to position the needle valve portion 18 relative to the discharge orifice 8 to determine the desired amount of opening thereof. The pump 29 being in operation oil under constant flow is driven from the source of supply 27 to the burner, the same entering through the intake pipe 105 20, which in view of its position tangent to the forward large end of said conical chamber 19 and immediately in back of said cap-plate 7, is compelled to gyrate or swirl rapidly around the interior of said chamber 110 19 in back of said cap-plate 7, so that the cyclonic effect or motion thereof causes a portion of the oil to be ejected through the discharge orifice 8 in the form of outwardly diverging spray, governed in quantity by 115 the amount of opening permitted to said discharge orifice by the adjusted position of the needle valve relative thereto. The remainder of the oil, so entering the chamber 120 19, with diminishing gyrating motion, due to the rearward contraction of the walls of said chamber 19, flows rearwardly through said chamber 19 to the outlet end 24 thereof, escaping therethrough into and through the passage 26, and thence through the out- 125 130

let pipe 22 into and through the return pipe line 30 back to the source of supply 27 on the suction side of the force pump 29. In this manner a constant flow or circulation 5 of oil through the chamber 19 of the oil burner is maintained, with the accompanying desired gyrating motion of the same in back of the cap-plate 7 and its discharge orifice 8, which is so necessary to the production 10 of the spray form ejection of the oil through the discharge orifice 8.

By the circulation of the oil so maintained in and through the chamber 19, all the disadvantages of the heretofore used types of 15 non-circulating oil burners above pointed out are avoided, and all the advantages which I claim, as also pointed out in the preamble of this specification, are attained.

Referring now to Figure 5 of the drawings, I have illustrated how my novel construction of oil burner may be used in series, an arrangement possessing many advantages not necessary to recite in detail, and not possible of attainment by non-circulating types of oil burners. In said Figure 5 I have shown three of my novel burners, A, B, and C so arranged that the supply pipe 28 is coupled with the intake pipe 20 of burner A, the outlet pipe 22 of burner A being coupled by intermediate piping D with the intake pipe 20 of burner B, and, in like manner, the outlet pipe 22 of burner B being coupled by intermediate piping E with the intake pipe 20 of burner C, while 35 the outlet pipe of burner C is connected with the return pipe 30. By this arrangement a continuous circulation of oil may be maintained through all the burners from a single source of supply and force pump, regardless of the open or closed condition of the 40 discharge orifice of any individual burner, so that the control of each burner may be individually attained, while a constant flow of oil is maintained through said burners 45 for use at the will of the operator. Of course, any number of burners may be coupled together in the above described manner.

I am aware that some changes may be made in the general arrangements and combinations of the devices and parts of my present invention, as well as in the details of the construction of said parts, without departing from the scope of my invention as set forth in the foregoing specification and as defined in the appended claims. Hence, I do not limit my invention to the exact arrangements and combinations of the devices and parts as described in said specification, nor do I confine myself to the exact details of the construction of said parts as illustrated in the accompanying drawings.

I claim:

1. An oil burner provided with a valve controlled spray discharge orifice, a rearwardly diminished conical chamber in back

of said discharge orifice, an oil intake means entering said chamber tangent to its largest circumference to cause the oil to gyrate therein in the rear of and about said discharge orifice, said chamber having an outlet at its rear small end, and an oil outlet means communicating with said chamber outlet. 70

2. An oil burner comprising a body portion providing a rearwardly diminished 75 conical chamber, a cap-plate having a centrally disposed spray discharge orifice closing the large open end of said chamber, an oil intake means entering said chamber tangent to its largest circumference immediately in back of said cap-plate, said body portion having an outlet passage communicating with the rear small end of said chamber, an oil outlet means connected with said outlet passage of said chamber. 80

85 3. An oil burner comprising a body portion providing a rearwardly diminished conical chamber, a cap-plate having a centrally disposed spray discharge orifice closing the large open end of said chamber, an oil intake means entering said chamber tangent to its largest circumference immediately in back of said cap-plate, said body portion having an outlet passage communicating with the rear small end of said chamber, an oil outlet means connected with said outlet passage of said chamber, a needle valve to co-operate with said discharge orifice, means connected with said body portion for mounting said needle valve, and a handle for manipulating said needle valve. 90 95

4. An oil burner comprising a body portion providing a rearwardly diminished conical chamber, a cap-plate having a centrally disposed spray discharge orifice closing the large open end of said chamber, an oil intake means entering said chamber tangent to its largest circumference immediately in back of said cap-plate, said body portion having an outlet passage communicating with the rear small end of said chamber, an oil outlet means connected with said outlet passage of said chamber, an internally threaded neck-portion centrally aligned and connected with the rear end of said body 105 portion, an externally threaded valve stem mounted in said neck-portion, said valve stem extending forwardly through said chamber and having a conical valve member to co-operate with said discharge orifice, and 110 the rearwardly and exteriorly projecting end of said valve stem having a handle for manipulating the same. 120

5. The combination with a combustion chamber of an air-intake conduit, an oil 125 burner within the discharge end of said air-intake conduit, said oil-burner having a valve controlled spray discharge orifice, a rearwardly diminished conical chamber in back of said discharge orifice, an oil intake 130

means entering said chamber tangent to its largest circumference to cause the oil to gyrate therein in the rear of said discharge orifice, said chamber having an outlet at its rear small end, and an oil outlet means communicating with said chamber outlet.

6. The combination with a combustion chamber of an air-intake conduit, an oil burner within the discharge end of said air-intake conduit, said oil-burner having a valve controlled spray discharge orifice, a rearwardly diminished conical chamber in back of said discharge orifice, an oil intake means entering said chamber tangent to its largest circumference to cause the oil to gy-

rate therein in the rear of said discharge orifice, said chamber having an outlet at its rear small end, and an oil outlet means communicating with said chamber outlet, means for connecting said oil intake and outlet means in circuit with an oil supply and means for circulating oil through said burner.

In testimony that I claim the invention set forth above I have hereunto set my hand this 20th day of December, 1919.

JAMES M. SEYMOUR, JR.
